Patented Nov. 21, 1922.

UNITED STATES PATENT OFFICE.

EMERY J. CHASZAR, OF DETROIT, MICHIGAN.

FURNACE.

Application filed August 31, 1921. Serial No. 497,120.

To all whom it may concern:

Be it known that I, EMERY J. CHASZAR, a citizen of the United States of America, residing at Detroit, in the county of Wayne and State of Michigan, have invented certain new and useful Improvements in Furnaces, of which the following is a specification, reference being had therein to the accompanying drawings.

10 A well known type of furnace has the bottom of its fire box or fuel basket some distance above the grate or shaker of the furnace, consequently when the shaker is operated live and useful coals are shaken from the side edges of the grate into the ash pit and wasted. Without interfering with the draft of such a furnace I provide a fuel retaining ring that may be readily installed to prevent the waste of fuel, obviate the necessity of screening or sifting ashes, and permit of lower grades of fuel in less quantities being used in the furnace.

15 My invention further aims to provide a fuel retaining ring that may be placed in old or new furnaces to form a retaining wall about the grate or shaker in the furnace, so that live coals or fuel cannot become laterally displaced but will remain on the grate until consumed.

20 My invention will be hereinafter described and then claimed, and reference will now be had to the drawing, wherein—

25 Figure 1 is a perspective view of the fuel retaining ring, and

30 Fig. 2 is a front elevation of a portion of the furnace partly broken away and partly in section, showing the ring in position.

35 In the drawing the reference numeral 1 denotes the lower portion of the furnace casing or shell in which is an ash box or pit 2 provided with a door 3 having a damper 4 and the top of the ash box 2 supports the lower end or section 5 of a fuel basket or combustion chamber 6.

40 In the ash box or pit 2 is a conventional form of grate 7 having a shaker ring 8 and the grate or ring may be shifted so as to shake down ashes and waste matter into the ash pit. The shaker ring 8 is ordinarily 45 some distance below the lower end of the combustion chamber leaving an annular gap

9 through which live coals may fall and enter the ash pit before completely burned and it is this waste of fuel that I aim to eliminate by providing the shaker ring with a fuel retaining ring.

45 The fuel retaining ring comprises an annular member 10 which may be mounted on the shaker ring 8 to provide an upstanding annular wall which will close the gap 9 to the extent of preventing fuel from working laterally off of the shaker ring when the same is shifted. The upper edges of the member 10 are in proximity to the lower edges of the combustion chamber and by 50 reference to Fig. 2 it will be noted that the upper edges of the annular member extend into the combustion chamber and consequently the member 10 cannot become laterally displaced.

55 In order not to interfere with any draft of the furnace particularly at the lower end of the combustion chamber, the annular member 10 has vent openings, preferably in the form of a series of inverted V-shaped notches 11 in the lower edge of the annular member and it is through these notches that air may pass to insure a proper combustion of fuel in the furnace.

60 The fuel retaining ring is made of durable metal that will withstand heat and fire of the furnace, and while in the drawing there is illustrated a preferred form of the ring, I reserve the right to make such changes as fall within the scope of the appended claims.

65 What I claim is:

1. The combination of a fuel basket, a shaker ring below said fuel basket, and a fuel retaining ring on said shaker ring and extending to the fuel basket to prevent fuel from being laterally shaken from the bottom of said fuel basket.

2. The combination set forth in claim 1, wherein the retaining ring has its lower edge notched to afford vent openings.

70 In testimony whereof I affix my signature in presence of two witnesses.

EMERY J. CHASZAR.

Witnesses:

KARL H. BUTLER,
G. E. MCGRANN.
